METAL CONTAINER HAVING A SOLDER-
LESS SIDE SEAM

Walter G. Plumb, Glen Rock, N. J., and Herbert Schrader, Wheeling, W. Va., assignors to Continental Can Company, Inc., New York, N. Y., a corporation of New York

Application June 27, 1936, Serial No. 87,774

1 Claim. (Cl. 226—81)

The invention relates to new and useful improvements in a sheet metal container having a body portion formed from a blank, the side edges of which are joined by a side seam.

6 An object of the invention is to provide a container of the above type wherein the side seam is made fluid-tight by the insertion of a non-metallic packing material which extends throughout the entire length of the side seam.

10 A further object of the invention is to provide a container of the above type wherein the body wall is shaped at both sides of interlocking portions of the side seam so as to prevent any lateral movement of the hooks due to collapsing stresses placed upon the outer face of the container body.

15 A still further object of the invention is to provide a container of the above type wherein the packing material is in the form of a strip secured to the body blank by cementing so that when the hooks are formed, said strip will lie within the inner hook and contact with the inner and outer faces of the outer hook.

20 A still further object of the invention is to provide a container of the above type wherein the packing strip is cemented to the body blank in the region from which the inner hook and inner lap portions are formed and prior to, during or after the notching of the blank and the bending of the same to form the hook.

25 30 These and other objects will in part be obvious and will be hereinafter more fully described.

In the drawing which shows by way of illustration one embodiment of the invention—

Figure 1 is a fragmentary plan view of a portion of the body blank from which the inner hook and the inner lap portions are to be formed with a packing strip applied to the body blank;

Fig. 2 is a view similar to Fig. 1, but showing the body blank at both side edges thereof slit and notched preparatory to the forming of the hooks;

Fig. 3 is a view similar to Fig. 2, but showing the body blank bent to form the hooks;

Fig. 4 is a sectional view through the side seam transversely thereof and prior to the submitting 45 of the body to a bumping action for completing the side seam;

Fig. 5 is a sectional view on the line 5—5 of Fig. 7;

Fig. 6 is a sectional view on the line 6—6 of 50 Fig. 7, and

Fig. 7 is a side elevation of a container embodying the improvements.

Many efforts have been made to produce a sheet metal can body wherein the side seam is made 55 liquid-tight without the use of a solder bond.

Such efforts have not been successful. One of the difficulties has been to produce a side seam which would be liquid-tight in the region where the lock portions join the lap portions. It is believed that applicants have overcome this difficulty by utilizing a packing material preferably in the form of a strip or gasket which extends throughout the entire region of the side seam. This packing strip or gasket is preferably made of paper, which paper may or may not be saturated with a sealing composition such as is commonly used in the forming of hermetic joints in interlocked metal parts. The preferred form of seam used in the joining of the side edges of the body blank is a lock and lap seam. The packing strip or gasket 15 is preferably attached to the body blank before the blank is notched and the hooks formed therein. It has been found that when a single packing strip is secured to the body blank so that it will extend throughout the entire length of the side seam including the lap portions, a very efficient liquid-tight joint is produced.

It is believed that the invention will be better understood by a more detailed description of the illustrated form thereof, as shown in the drawing. The body blank which is shaped into the container body is indicated at B. A pre-formed packing strip or gasket S preferably of paper is secured to the body blank along the side edge thereof. This strip is of a width substantially 25 equal to twice the length of the inner hook. After the strip has been secured to the body blank, then the body blank is subjected to the usual slitting and notching devices so that slits 10 are formed in the body blank and in the packing strip and notches 11 are formed at the other side edge of the body blank. The body blank is then presented to the usual devices for forming the hooks and the metal between the notches 10, 10 is folded back to form the hook 12. Inasmuch as the 30 packing strip S is substantially twice the width of the inner hook, the packing strip will extend across the inner face of the inner hook and along the outer face of the body wall to the extent of the overlap of the inner hook. At the same time that the hook 12 is formed, the body blank is 35 bent to form the outer hook 13.

It will be noted that the packing strip or gasket not only lines the inner face of the inner hook but also extends across and covers the lap portions 14, 14. After the hooks are formed, the blank is shaped into body form and the hooks interlocked as indicated in Fig. 4. The interlocked hooks and body are then subjected to a bumping action which completes the formation of 40 45 50 55 60 65 70 75 80 85 90 95 100 105 110 115 120 125 130 135 140 145 150 155 160 165 170 the side seam. During this bumping action, the body wall is sharply bent so that it lies close to the base of the inner hook 12. This is indicated at 15 in Fig. 5 of the drawing. The body will is also bent outwardly and shaped as indicated at 16 in Fig. 5. This portion 16 lies close to the base of the outer hook 13. The purpose of these sharply bent portions at each side of the side seam is to hold the interlocked hooks in engagement with each other. Any internal pressure created on the can wall tends to draw the hooks together. Any external pressure on the body wall in the region of the side seam tends to unlock the hooks by collapsing the body wall and shortening the circumferential extent thereof. When the hooks are solder bonded, the hooks cannot be interlocked without shearing the solder bond. When, however, a packing strip or gasket is used, some mechanical means is necessary to prevent this engagement of the hooks or any movement of one hook relative to the other which is likely to produce a leak. The shaping of the side seam, as above noted, prevents any lateral movement of the hooks relative to each other which would disengage the hooks sufficiently to cause a leak.

Furthermore, when the wall of the container body adjacent the side seam is shaped so as to provide a rib extending along the base of the outer hook, this rib becomes a girder which operates to strengthen the seam and prevent any bending of the body wall from shocks or blows against the outer surface thereof. When the side seam is strengthened by this girder and the hooks positively held interlocked, then the container can be placed under vacuum and the differential pressure on the side seam will not cause any bending or bowing of the side seam with resulting leaks. When the side seam is bumped and the hook portions brought into firm contact with the packing strip or gasket S, the lap portions 14 are also caused to firmly contact with the packing strip. After the can body has been formed, it is flanged and then the bottom end E is secured thereto by double seaming in the ordinary manner. The entire lap portions are rolled into the side seam and this will bind the lap portions against the packing so firmly that a liquid-tight joint is obtained at the juncture between the lock portions of the side seam and the lap portions of the side seam.

After the container is filled, then the top end E' is secured by double seaming and this likewise produces a liquid-tight joint at the juncture between the upper end of the lock portions of the side seam and the adjacent lap portions of the side seam.

The paper packing strip or gasket without any special treatment, when extended throughout the entire length of the side seam including the lap portions, will produce a liquid-tight joint. It is, however, found preferable to saturate the paper either before or after it is applied, with a sealing material such as is used in the form-

ing of hermetic joints at the double seams. It is preferable to secure the packing strip to the metal blank which is to form the body by cementing the strip to the blank prior to the forming of the hook and the lap portions, for in this manner the packing strip can be placed quickly and accurately so that it extends throughout the entire length of the side seam and is so disposed relative to the interlocking and lapping portions as to produce a fluid-tight joint. While it is preferred to apply the packing in the form of a strip, it will be understood that it may be otherwise applied, but it is essential that there shall be a portion of the packing strip or gasket extending throughout the entire length of the side seam including the interlocking hooks and the lapping portions at the end thereof. In fact, in the finished container, this packing strip not only extends throughout the entire length of the side seam but into the double seam so as to insure a liquid-tight joint in the region where in the side seam merges into the double seams.

When the container is provided with a liquid-tight side seam such as described above and without the use of solder, the body may be formed from black sheet metal or any other type of metal which it is difficult to solder. Furthermore, when a liquid-tight joint is produced without the aid of heat, then the body blank can be decorated all the way up to the side seam hooks and thus a continuous peripheral decoration obtained. It is further obvious that when the side seam is made liquid-tight without the use of solder, the container can be fabricated at a less expense.

It is obvious that other forms of side seams may be used for joining the edges of the body blank, and other types of notches may be used in connection with a lock and lap seam. It is essential, however, that the packing material shall extend throughout the entire limits of the side seam and into the end seams joining the ends to the can body.

Having thus described the invention, what we claim as new and desire to secure by Letters Pat- ent is—

A sheet metal container comprising a body portion having its edges joined by a side seam including oppositely disposed interlocking hooks, lap portions at the ends of the side seam, closure ends seamed to said body portion, a paper gasket saturated with a sealing composition disposed between the adjacent faces of the hooks and extending as a continuous packing strip between the lap sections and into the double seam joining the closure ends to the body portion, said body being shaped at each side of the side seam so as to hold said hooks firmly interlocked when subjected to stress on the exterior of the container body.
